United States Patent Office

Des. 191,717

Patented Nov. 7, 1961

191,717

COMBINED CAN PUNCH AND SPOUT

Richard W. Cooper, Hutchinson, Kans., assignor to Tri-Co Manufacturing, Inc., Hutchinson, Kans., a corporation of Kansas

Filed Jan. 13, 1961, Ser. No. 63,550

Term of patent 14 years

(Cl. D44—29)

Fig. 1

Fig. 2

Fig. 3

Fig. 4

Fig. 5

FIG. 1 is a perspective view of a combined can punch and spout showing my new design;

FIG. 2 is a rear elevational view thereof;

FIG. 3 is a front elevational view thereof;

FIG. 4 is a side elevational view thereof; and

FIG. 5 is a top plan view thereof.

I claim:

The ornamental design for a combined can punch and spout, as shown.
